US00D949284S

(12) **United States Design Patent** (10) **Patent No.:** **US D949,284 S**
(45) **Date of Patent:** **** Apr. 19, 2022**

(54) **BASE FOR WATER PURIFICATION FILTER**

(71) Applicant: **Ningbo Eastpure Environmental Technology Co., Ltd.**, Ningbo (CN)

(72) Inventor: **Yanfeng Xu**, Ningbo (CN)

(73) Assignee: **Ningbo Eastpure Environmental Technology Co., Ltd.**, Ningbo (CN)

(**) Term: **15 Years**

(21) Appl. No.: **29/759,068**

(22) Filed: **Nov. 19, 2020**

(30) **Foreign Application Priority Data**

Nov. 3, 2020 (CN) 202030661891.1

(51) **LOC (13) Cl.** **23-01**

(57) **CLAIM**

The ornamental design for a base for water purification filter, as shown and described.

DESCRIPTION

FIG. 1 is a perspective view of a base for water purification filter, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.
